UNITED STATES PATENT OFFICE.

WALTER R. DIEHL, OF PITTSBURGH, PENNSYLVANIA.

DRAFT-RIGGING FOR RAILWAY ROLLING-STOCK.

1,155,896.

Specification of Letters Patent.

Patented Oct. 5, 1915.

Application filed January 26, 1915. Serial No. 4,521.

To all whom it may concern:

Be it known that I, WALTER R. DIEHL, a citizen of the United States of America, and resident of Pittsburgh, in the county of Allegheny and State of Pennsylvania, have invented certain new and useful Improvements in Draft-Rigging for Railway Rolling-Stock, of which the following is a specification.

- 10 This invention relates to draft rigging for railway rolling stock and particularly to means adapted to coact with the draw-bar for minimizing the shock and strain due to drafting and buffing of such railway rolling stock, it being understood that there is included within the term "railway rolling stock" all that equipment movable on the rails having means of connection one with the other, such as cars and locomotives.
- 15 The main object of the invention having been stated, the invention has for its further object the provision of means whereby there is an absorption of the vibration and jar incident to the coupling and movement of the 20 railway rolling stock, the means of absorption in the present embodiment of the invention being interposed between the draw-bar and the means for connecting the draw-bar to the sills, usually the center sills of 25 such railway rolling stock, the present embodiment of the invention consisting more 30 specifically in the provision of interposed mechanism in which friction disks and springs are a part of the whole, constituting 35 an efficient and satisfactory means for absorbing the shock and strain of buffing so that the durability of such railway rolling stock is prolonged and increased as compared with railway rolling stock having 40 equipment now in common use.

With the foregoing and other objects in view, the invention consists in the details of construction, and in the arrangement and combination of parts to be hereinafter more 45 fully set forth and claimed.

In describing the invention in detail, reference will be had to the accompanying drawings forming part of this specification, wherein like characters denote corresponding 50 parts in the several views, and in which—

Figure 1 illustrates a top plan view of a draft rigging embodying the invention; Fig. 2 illustrates a sectional view on the line 2—2 55 of Fig. 1; Fig. 3 illustrates a sectional view

on a line corresponding to the line 3—3 of Fig. 2; Fig. 4 illustrates an end view of a combined follower and friction disk; Fig. 5 illustrates a side elevation of the combined follower and friction disk showing a plate 60 or disk rod associated therewith; Fig. 6 illustrates an end view of the device as it appears in Fig. 5; Fig. 7 illustrates a face view of a friction disk or plate; Fig. 8 illustrates a sectional view thereof; Fig. 9 illustrates a side elevation or face view of a stationary friction disk; Fig. 10 illustrates a sectional view thereof; Fig. 11 illustrates a friction disk of another form; and Fig. 12 illustrates a sectional view thereof.

In these drawings 15 denotes a shell or housing of a friction gear on the inner surface of which there is a plurality of spirals or helices 16 and 17 which coöperate with fins or lugs 18 projecting from the edges of 70 the rotating friction disks 19, the said lugs having beveled surfaces 20 forming cams which engage the spirals of the housing so that the camming action resulting between the said beveled surfaces and the said spirals 75 results in rotating or turning the disks when movement is imparted to said disks longitudinally of the housing as is the case, as will presently appear, when pressure or pull is 80 exerted through the draw-bar.

At one end of the housing, there is a follower 21 having its rear face provided with a vertically disposed slot 22 forming a seat for the yoke 23, the said yoke having its outer extremity connected to a draw-bar 24 90 so that movement of the draw bar is communicated to the yoke as in ordinary draft rigging.

25 illustrates the ordinary end sill of a car frame and 26 the ordinary center sills of 95 such car frame construction, the said center sills constituting guides and supports for the shock absorbing mechanism.

The follower 21 has a body portion 27 from which a disk or plate rod 28 extends, 100 the said rod being angular in cross section to receive stationary friction disks, such as 29 and 30 having central apertures 31 and 32 respectively, which receive the rod and interlock therewith so that the said disks 105 are stationary or at least are prevented from rotation on the rod. The stationary disks are intended to act with the movable or rotating disk and the faces of the stationary and rotating disks are of complementary 110

construction, the said stationary disk being here shown as having convexed side surfaces and the rotating disk as having side convexities so that when the disks are forced into contact, the rotating disks will frictionally engage and ride on the stationary disk and the relative movement of these disks will serve to absorb shock and vibration incident to the coupling of cars and rolling stock.

10 Within the housing and coacting with the disks for the purposes stated, is a plurality of tension springs, preferably of unequal strength and rigidity, the said invention being here shown as having a relatively 15 heavy outer spring 33, a somewhat weaker intermediate spring 34 and a relatively light inner spring 35, the said spring being coiled one around the other successively from the inner to the outer spring and the said 20 springs have their ends abutting one of the disks on the disk rod and the opposite ends abutting a shoulder of the casing or the inner end of the draft bar, it being seen from an inspection of Fig. 1 of the drawings 25 that the outer or heavier spring 33 engages the shoulder 36 and the other springs engage the inner end of the draft bar.

The construction or manner of assembling the disk rod and the follower is immaterial 30 as they may be separate or integral according to the wishes of the manufacturer, and as this detail of construction is not important and may be modified to suit particular requirements, the said joint between these 35 parts is not shown.

In operation, the assembled or nested springs within the housing collectively operate to maintain an initial pressure on the 40 disks situated on the disk rod and the spirals or helices of the shell or housing regardless of whether the said disks are stationary as regards their rotation or are rotatable with relation to the stationary disks.

The casing and parts associated therewith 45 are supported between the center sills 26 on the longitudinal guides 37 and the longitudinal movement of the shock absorbing mechanism with relation to the guides is limited by the lugs 38 at the outer end and 50 the lugs 39 at the inner end.

When in operation, draft is exerted on the 55 coupler, the shell or housing abuts the lugs 38 through the draw-bar and yoke and the follower is drawn or forced into the casing or housing, carrying with it the friction disks or plates which are on the disk rod and such action compresses the outer spring, thus gradually increasing the frictional contact 60 between the disks and serving to retard the movement of the follower with relation to the casing for it is to be seen from the drawing and from the foregoing description that the movement of the disks 19 longitudinally of the casing results in their rotation because of the engagement of the lugs thereof

with the helices, such rotation of the movable disks with relation to the stationary disks serving to create a grinding or frictional engagement between the faces of said disks, which aids in retarding the movement 70 of the follower yet affording such yielding action as to preclude undue shock or vibration.

It is the purpose of the inventor to regulate the frictional contact or engagement of 75 the rotating disks and the stationary disks and this may be done by diminishing the tension of the springs or by increasing or diminishing the number of pairs of stationary and rotatable friction disks. 80

In the arrangement shown in the drawing, the inner springs which have their ends abutting the draw-bar are of uniform tension during the operation of the device, since they are free to follow the draw bar. Their 85 function, therefore, is to maintain an initial and uniform tension on the friction disks whereas the outer spring has its tension increased or diminished according as the follower moves longitudinally of the casing. 90

The follower may butt the buffer lugs 39 when the coupler is forced back in which 95 operation, the shell or housing with the friction disks and springs are forced back over the follower and this reversal of movement results to the same degree in causing the rotation of the movable disks and the increase of pressure on said disks, due to the compression of the outer spring, thus making it possible for the device to operate regardless of whether the rolling stock is 100 buffed or drawn.

The construction, operation and advantages of this invention will be apparent 105 from the foregoing specification and it will be obvious that various changes may be resorted to in the proportions and details of construction, as fall within the scope of the appended claims. 110

I claim

1. In a friction draft gear, the combination of a coupler-draw-bar and yoke, a housing, guides whereby the housing is supported to move longitudinally of a car, rotatable friction disks in the housing, stationary friction disks with relation to and in engagement with which the movable disks travel, means for communicating the motion of the draw bar to the disks, means for guiding the disks longitudinally of the housing, means for causing the rotation of the movable disks during their travel. 115

2. In a friction draft gear, the combination of a coupler-draw-bar and yoke, a housing, longitudinal guides on which the housing is movable, guides for the yoke, helices interiorly of the housing, friction disks supported within the housing, means for holding the friction disks in contact, means on certain of the friction disks for engaging 120 125 130

the helices, means for moving the disks longitudinally of the casing, whereby the means engaging the helices causes rotation of the disks, and means for communicating the motion of the draw bar to said disks.

3. In a friction draft gear, the combination of a coupler-draw-bar and yoke, a housing, longitudinal guides on which the housing is movable, guides for the yoke, helices 10 interiorly of the housing, friction disks supported within the housing, means for holding the friction disks in contact, means on certain of the friction disks for engaging the helices, means for moving the disks 15 longitudinally of the casing, whereby the means engaging the helices causes rotation of the disks, means for increasing the tension on the disks as they move longitudinally of the housing, and means for communicating the motion of the draw-bar to 20 said disks.

4. In a friction draft gear, the combination of a coupler-draw-bar and yoke, a housing, guides in which the housing is supported and with relation to which said housing is slid able, yoke guides, means for coupling the yoke to the draw bar whereby the movement of the draw bar is communicated to the yoke, helices interiorly of the housing, 30 an annular shoulder near the end of said housing, a series of friction disks arranged in two series, one series of which is stationary and the other of which is rotatable, means on the rotatable disks engaging the helices, means for moving the disks longitudinally of the casing whereby the camming action of the helices communicates motion to the rotatable disks, and means for holding one series of friction disks in contact with the other series thereof.

5. In a friction draft gear, the combination of a coupler-draw-bar and yoke, a housing, guides in which the housing is supported and with relation to which said housing is slid able, yoke guides, means for coupling the yoke to the draw bar whereby the movement of the draw bar is communicated to the yoke, helices interiorly of the housing, an annular shoulder near the end 50 of said housing, a series of friction disks arranged in two series, one series of which is stationary and the other of which is rotatable, means on the rotatable disks engaging the helices, means for moving the disks 55 longitudinally of the casing whereby the camming action of the helices communicates motion to the rotatable disks, means for normally holding the friction disks in contact and means for increasing the pressure 60 of the disks against one another according to the longitudinal movement of said disks.

6. In a friction draft gear, the combination of a coupler-draw-bar and yoke, a housing, guides on which the housing is longitudinally movable, helices and an annular

shoulder interiorly of the housing, rotatable and non-rotatable friction disks within the housing, means for supporting them in assembled relation, means for moving the friction disks longitudinally of the housing, 70 means for turning the rotatable disks as said disks are moved longitudinally of the housing, and means for communicating the motion of the draw bar to said housing.

7. In a friction draft gear, the combination of a coupler-draw-bar and yoke, a housing, guides on which the housing is longitudinally movable, helices and an annular shoulder interiorly of the housing, rotatable and non-rotatable friction disks within the 80 housing, means for supporting them in assembled relation, means for moving the friction disks longitudinally of the housing, means for turning the rotatable disks as said disks are moved longitudinally of the casing, 85 and means for holding the rotatable disks in frictional contact with the non-rotatable disks.

8. In a friction draft gear, the combination of a coupler-draw-bar and yoke, a housing, guides on which the housing is longitudinally movable, helices and an annular shoulder interiorly of the housing, rotatable and non-rotatable friction disks within the 90 housing, means for supporting them in assembled relation, means for moving the friction disks, longitudinally of the housing, means for turning the rotatable disks as said disks are moved longitudinally of the 95 housing, means for holding the rotatable disks in frictional contact with the non-rotatable disks, and means for increasing the pressure on the disks as they move longitudinally of the casing.

9. In a friction draft gear, the combination of a coupler draw-bar and yoke, a housing, means for supporting the housing whereby it may move longitudinally of a car, helices and an annular shoulder interiorly of the housing, two series of alternating friction disks, a rod for supporting the said disks, projections on the edges of the rotatable disks engaging the helices of the casing, whereby movement of the disk longitudinally of the casing results in the rotation of said disks, a tension member having one end engaging an end disk and the opposite end engaging the shoulder of the housing whereby pressure is exerted on the said disk, and means for communicating the motion of the draw bar to said disks.

10. In a friction draft gear, the combination of a coupler-draw-bar and yoke, a housing, means for supporting the housing to move longitudinally, guides for the yoke, 125 helices and an annular shoulder within the housing, rotatable and non-rotatable disks alternately positioned in the housing, means on the rotatable series for engaging the helices and intermeshing therewith to turn said 130

disks while they move longitudinally of the housing, a follower having a rod on which the non-rotatable disks are mounted, tension members bearing against the end disk 5 of the series and against the shoulder of the housing, and tension members bearing against the end disk and against the draw-bar.

11. In a friction draft gear, the combination of a housing having internal helices 10 and an annular shoulder or spring seat at one end of the housing, said housing having an opening through its end for the passage of secondary buffering springs adapted to be seated against a draw-bar.

12. In a friction gear, the combination of a shell or housing having internal helices and an annular shoulder or spring seat at 20 one end of the housing, said housing having an opening through its end, a draw bar connected to the end of the housing, friction disks in the housing, a spring interposed between the end friction disk and the annular shoulder for exerting pressure to 25 increase the frictional contact of the disks, springs engaging the end disk and having their opposite ends through the opening in the housing and bearing against the draw bar, means for communicating motion to the 30 disks longitudinally of the casing, and means on certain of the disks for engaging the helices of the housing whereby movement of

the disks longitudinally of the casing results in rotating said disks.

13. In a friction draft gear, the combination of a housing having internal helices, a follower, means for mounting the follower and housing whereby they have movement longitudinally of each other, friction disks carried by the follower, means for holding 35 the disks in frictional contact, means for creating relative movement of the follower, and housing, and means whereby said movement communicates rotary motion to certain of the friction disks. 40

14. In a friction draft gear, the combination of a series of single acting tension springs and a series of contacting frictional disks, double acting drafting and buffering springs for increasing the frictional contact 45 of the disks, means for communicating motion of a draw bar to the double acting springs and housing, means for creating relative movement of the disks and housing, and means for causing the rotation of certain of the friction disks during such relative movement. 50

In testimony whereof, I affix my signature in the presence of two witnesses.

WALTER R. DIEHL.
